UNITED STATES PATENT OFFICE.

CHARLES H. WATSON, OF MALDEN, MASSACHUSETTS.

SPOOL.

SPECIFICATION forming part of Letters Patent No. 366,800, dated July 19, 1887.

Application filed October 27, 1886. Serial No. 217,305. (No model.)

To all whom it may concern:

Be it known that I, CHARLES H. WATSON, a citizen of the United States, and a resident of Malden, in the county of Middlesex and State of Massachusetts, have invented new and useful Improvements in Spools, of which the following, taken in connection with the accompanying drawings, is a specification.

This invention relates to improvements in spools; and it is carried out as follows, reference being had to the accompanying drawings, where—

Figure 1 represents a central longitudinal section of my improved spool. Fig. 2 represents a top view of it; and Fig. 3 represents a cross-section on the line A. B, shown in Fig. 1. Figs. 4 and 5 represent, respectively, in plan view and longitudinal section a modification of my invention.

Similar letters refer to similar parts wherever they occur on the different parts of the drawings.

This invention has for its object to provide spools with a convenient case or receptacle in which to temporarily insert needles or pins, so as to be within easy reach whenever needed for use; and with this object in view my device is constructed as follows:

a is the spool-body as usual, with its central longitudinal perforation, a', as shown in the drawings. At one side of the central perforation, a', I make in the spool-body a cylindrical perforation or recess, b, preferably not extending through the entire length of the spool, as shown in Fig. 1, and such bore or recess I fill with sawdust, cotton, sponge, fiber, or suitable material, d, in which to stick and temporarily retain the pins or needles c c, as shown in Fig. 1. To prevent the material d from dropping out of the recess b when the spool is transported or handled, I cover the open end of such recess with a cloth, leather, or other suitable washer, e, which is preferably held in place by means of the metal ring f, having

downwardly-projecting prongs f' f' f', that are driven into the upper portion of the spool, as shown in Figs. 1 and 2.

If so desired, the central perforation, a', may be utilized by locating within it a tube, g, of smaller outside diameter than the interior 50 diameter of such central perforation and placing a filling material, h, in the annular space between the tube and recess, as represented in Figs. 4 and 5, which would then serve in the same manner as a pin or needle 55 case. By this arrangement it will be seen that the central perforation in the spool is not in any way obstructed, and can be utilized as usual to introduce within it the usual spool-holding spindle on which the spool is commonly supported on sewing-machines, and the improved spool can be placed on a spindle in the usual manner while in the act of winding the thread upon it or unwinding the same.

What I wish to secure by Letters Patent and 65 claim is—

1. A spool having a recess, b, open in one end and provided with a suitable filling material, d, or its equivalent, as described, in combination with the metal or other holding-ring f, as and for the purpose set forth.

2. A spool having a recess, b, open in one end, and there provided with a cloth or other washer, e, and metal or other holding-ring f, and having within said recess a suitable filling 75 material, d, or its equivalent, as described, the whole being arranged and constructed substantially in a manner and for the purpose set forth.

In testimony whereof I have signed my name 80 to this specification, in the presence of two subscribing witnesses, on this 23d day of October, A. D. 1886.

CHARLES H. WATSON.
